UNITED STATES PATENT OFFICE

JOHN V. PALMER, OF PITTSBURGH, PENNSYLVANIA, ASSIGNOR OF ONE-THIRD TO HARRY I. NEAMAN AND ONE-THIRD TO JAMES M. MAGEE, BOTH OF PITTSBURGH, PENNSYLVANIA

RAIL COUPLING

Application filed October 17, 1928. Serial No. 313,129.

This invention relates to an improved rail coupler.

One object of the invention is to provide a rail coupler which will effectually retain the meeting ends of railroad rails in coupled relation.

Another object of the invention is to provide a rail coupler which will eliminate the use of nuts, washers, or the like for connecting the rail ends.

10 A further object of the invention is to provide a rail coupler which may be easily installed and which will not work loose when in position.

15 Other objects of the invention not specifically mentioned in the foregoing will be apparent during the course of the following description.

In the accompanying drawings:

20 Figure 1 is a perspective view showing the device in position,

Figure 2 is a top plan view of the device,

25 Figure 3 is a sectional view of the device on the line 3—3 of Figure 2 looking in the direction indicated by the arrows,

Figure 4 is a perspective view showing more clearly the chair plate employed in the device,

30 Figure 5 is a perspective view showing more clearly the openings provided in the meeting end portions of the rails.

Referring now more particularly to the drawings, the numeral 1 indicates the meeting end portions of railroad rails provided 35 with flanges 2, webs 3, and openings 4.

I employ a substantially rectangular chair plate 5 having a bottom wall 6 and inwardly disposed overhanging flanges 7. Formed medially in the inner edge of each flange is 40 a notch 8 substantially rectangular in shape. Formed on the bottom wall 6 and disposed at each end portion thereof are pairs of upstanding studs 9 loosely engaging in the openings 4 of the rails 1, said studs being slightly 45 smaller in diameter than the openings to provide for expansion and contraction of the rails.

Associated with the chair plate 5 are wedge plates 10 having bodies 11 and flanges 12 and 50 13 straddling the flanges 7 of the chair plate.

The flanges 12 are each provided with curved upper faces of different radius, and the flanges 12 terminate flush with the side walls of the chair plate 5. The upper flanges closely overlie the flanges 7. The lower flanges 13 are provided with horizontal top faces lying against the bottom faces of the flanges 7 and the flanges 13 are tapered from end to end to define laterally and longitudinally inclined bottom faces resting flat against the upper faces of the base flanges 2 of the rails. Thus the bottom flanges 13 tightly wedge between the flanges 7 of the chair plate and the flanges 2 of the rails so that the wedge plates limit the rail ends against upward displacement in the chair plate. The bodies of the wedge plates engage the rail webs for bracing the rail ends against lateral movement. Formed in the bodies of the wedge plates are recesses 14 and extending through 70 said recesses is a conventional conductor 15 for carrying the current required to operate signals and the like. Formed medially in the upper flanges of the wedge plates at the junction of the curved top faces thereof are 75 openings 16 and fitting through said openings into the notches of the chair plate are keys 17 substantially square in shape.

The keys are provided with heads having knob like projections 18 at the rear ends thereof and, as will be observed, the keys are curved longitudinally so that when said keys are driven into place, the lower ends thereof bind in the notches 8 of the chair plate while the projections 18 of the heads of the keys are forced beneath the rail tread to bind against the lower corners thereof for locking the keys against accidental upward retraction as well as locking the upper end portions of said keys in binding engagement with the upper end portions of the walls of the openings 16 of the wedge plates. Accidental release of the keys such as might be caused by vibration will thus be prevented. However, the heads of the keys are provided with notches 19 to accommodate a suitable tool for withdrawing the keys.

In use, the meeting ends of two rails are inserted in the chair plate with the studs loosely fitting in the openings 4. The wedge 100

plates are then inserted and driven in until the openings 16 align with the notches 8. The keys 17 are then inserted and driven into position for locking the wedge plates against retraction so that the rails 1 are securely connected in joined position.

Having thus described the invention, I claim:

1. A rail coupling including, in combination with rails having flanges, a chair plate having overhanging flanges provided with notches, wedge plates engaging in the chair plate and having upper flanges, said upper flanges being provided with openings to align with the notches in the chair plate when the wedge plates are driven into position, and keys extending through the openings and into the notches and locking the wedge plates in position, said keys being longitudinally curved to coact with the walls of said openings for locking the keys against retraction.
2. A rail coupling including, in combination with rails having webs, treads and flanges, a chair plate having overhanging flanges, wedge plates having bodies engaging the webs of the rails and bottom flanges tapered to wedge between said flanges of the chair plate and the flanges of the rails for limiting the rails against displacement, and headed keys locking the wedge plates in position and being longitudinally curved to coact with said wedge plates and with the chair plate for binding the heads of said keys in engagement with the rail treads for locking said keys against retraction.

In testimony whereof I affix my signature.

JOHN V. PALMER. [L. s.]
